PIANO ACCORDION

Frank Kostka, Buffalo, N. Y.

Application October 12, 1942, Serial No. 461,718

17 Claims. (Cl. 84—376)

This invention relates generally to musical instruments, but more particularly to certain new and useful improvements in piano accordions.

It has for one of its objects to improve the construction of the reed block assembly of such instruments to prevent leakage of air about the reeds as well as from the reed chamber and thereby insure the proper volume of air for effectively operating the reeds in obtaining a uniformity of tone volume and quality.

Another object of the invention is to provide the accordion with means for readily and accurately effecting a key transposition of from one-half to one and one-half tones in either direction, whereby the musical range and capacity of tone production may be increased at the will of the player.

A further object is to provide a piano accordion having a simple and reliable switching mechanism for controlling the actuation of the valve assembly to in turn govern the tone effects for simulating or resembling the violin, the cello and other musical instruments.

A still further object of the invention is to so construct and mount the playing keys that they may be readily adjusted individually to maintain the keyboard even and smooth as to render the key action shallow or deep, the adjustment being so designed as not to disturb the valve-controlling extensions of the keys.

Other features of the invention reside in the construction and arrangement of parts herein-after described and particularly pointed out in the appended claims.

In the accompanying drawings:

Figure 1 is a front elevation of the piano accordion embodying my improvements. Figure 2 is an end view thereof. Figure 3 is an enlarged fragmentary top view of the same with the cover plate removed. Figure 4 is an enlarged fragmentary cross section taken substantially in the plane of line 4—4, Figure 1. Figure 5 is an enlarged horizontal section taken between the top plate of the windchest and the adjustable reed block and substantially in the plane of line 5—5 of Figure 4. Figure 6 is a fragmentary transverse section taken on line 6—6, Figure 5. Figure 7 is a fragmentary longitudinal section taken substantially in the plane of line 7—7, Figure 4. Figure 8 is a fragmentary end view partly in section of the reed block and key connections to the valves thereof. Figure 9 is a fragmentary bottom perspective view of the reed block. Figure 10 is a fragmentary perspective view of the lever control mechanism for the top row of reed valves,

Similar characters of reference indicate corresponding parts throughout the several views.

In the preferred embodiment of my invention shown in the drawings the accordion consists generally of a rectangular frame 10 on one side of which is mounted a bellows 11, while on its opposite side and communicating with the bellows through air passages 12 is a windchest 13 in which is mounted a unitary reed block assembly 14 capable of adjustment therein for transposing purposes; a keyboard 15 extending at the customary angle to the accordion frame and in adjoining relation to the windchest and having its white and black keys 16 and 17, respectively, grouped in the usual fashion to form the piano key assembly; and a stop or switch assembly, wherein the selective control levers thereof are indicated by the numeral 18, mounted on the top side of the windchest between it and the piano key assembly for conveniently controlling at the will of the player the tone-producing units or reeds in a manner to simulate or imitate the tonal effects of a violin, cello, and other musical instruments. A suitable hood or cover plate 19, ornamented if desired, may extend over the top side of the windchest and below the selective levers 18 to conceal the operating mechanism controlled by the latter. These are marked with suitable identifying characters, as "Violin," "Cello," "Full acc'n," etc.

Applied to the top side of the windchest 13 is a metallic plate 20 of aluminum or like material which is provided therein with a plurality of longitudinal rows of air outlet ports or passages 21 which are equally spaced and preferably square or rectangular in shape, and which are arranged in two adjoining groups inwardly of the keyboard in correlation with the player keys thereof. The passages in the several rows of each group are transversely aligned and for each playing key there are four of such passages. The passages in the several rows are spaced or separated longitudinally by comparatively narrow webs 22, while in a direction transversely of the plate these passages are spaced by somewhat wider webs 23. Mounted on the top side of this plate 20 are a plurality of vertically-swinging valves or reed controls 24 disposed parallel to and coextensive with the companion rows of plate-openings 21 for normally closing them, and operatively connected to the companion switch levers 18 for controlling the escape of air through such openings and accordingly governing the tone-producing units or reeds to imitate the tonal effects of a violin, cello, or the like. These valves are each faced with a

sealing strip 25 to insure an air tight seal in their closed position, and one or more springs 26 are associated with each valve to normally retain them in and urge them to a closed position.

The reed block 14 is a unitary structure containing two groups of reed chambers A and B for operative control by the companion white and black keys 16 and 17, respectively, and is preferably supported on the underside of the plate 20 for communicating registration at its top side with the companion groups of outlet passages 21 thereof and for adjustment lengthwise of the windchest 13 for effecting a key transposition of from one-half to one and one-half tones in either direction to vary the musical range and capacity of tone production at the will of the player. At its bottom side the reed block is provided with a plurality of valves 27 for controlling the flow of air from the windchest through the chambers A and B thereof, said valves being connected to the playing keys for selective operation thereby. Each of these valves seats over a plurality of rectangular-shaped ports 28, three being shown in the drawings, formed in the bottom wall 29 of the reed block and communicating with companion reed chambers. For transposing purposes, the reed block has extra or additional reed chambers at its opposite ends.

Each group of reed chambers is preferably formed by providing two longitudinal partitions 30 extending from the top to the bottom of the block, resulting in three rows of reed chambers 31, 32 and 33 which are divided at equally spaced intervals by transverse partitions 34 having substantially upright grooves or guideways 35 in their opposite side faces for removably supporting reed-bearing plates 36. There are four reed plates for each key arranged in each resulting transverse row of these partitioned chambers, two of the reed plates being disposed in spaced adjoining relation substantially centrally of the middle reed chamber 32, while the other two are arranged in each of the end reed chambers 31 and 33 in like spaced relation to the companion partitions 30. At their upper ends and in the spaces resulting between the central pair of reed plates and between the end reed plates and the companion longitudinal partitions, these reed chambers are closed or sealed airtight by sealing strips 37, whereby the three reed chambers at their upper ends define four rows of transversely aligned outlets 38 of rectangular shape in plan which communicate with the companion rows of ports 21 in the plate 20. It will be noted that the two center rows of outlets 38 are common to and communicate with the middle reed chamber 32 at either side of their companion pair of reed plates 36, while the end rows of outlets communicate with the companion end chambers 31, 33 between the reed plates thereof and the opposing walls of the block. Of the three rows of the valve-controlled ports 28 formed in the bottom wall of the reed block, the center row thereof communicates with the middle reed chamber 32 between the companion pair of reed plates 36 arranged therein, while the end rows of such ports communicate with the end chambers 31 and 33 between the reed plates arranged therein and the companion partitions 30. Each reed plate carries a pair of reeds 39 and 40, one operating by inflow of air past the reed and the other upon outflow for producing the same pitch or tone.

In width the plate-ports 21 and the reed chamber outlets 38 are the same, while in length the

latter are approximately twice as long as the former and the transverse partitions 34 are approximately twice the width of the transverse webs 22 between the plate-ports, whereby each 5 reed chamber may bridge and register with two adjoining plate-ports. In the example shown in the drawings, there are provided three extra reed chambers for each row of plate-ports, so that when the reed block 14 is adjusted lengthwise of the windchest, in one direction or the other, the key transposition can be effected to from one-half to one and one-half tones.

The adjustment of the reed block is accomplished by a knob 41 applied to the upper end 15 of an upright shaft 42 journaled in a bracket 43 applied to the top side of the plate 20 and having a pinion 44 at its lower end meshing with a rack bar 45 secured to the top side of the reed block between the two groups of reed chambers. 20 The shaft has a radial pin 46 projecting therefrom for engagement with companion radial notches 47 formed in a plate 48 secured to the bracket 43 and a spring 49 coiled about this shaft below its pin normally urges and maintains the 25 knob in a set position of adjustment. For each transposing adjustment of the knob 41, the reed block is moved a distance equal to the length of the plate-ports 21 and in order to observe the adjustment, the block has an indicator pin 51 rising therefrom which is adapted to register with a transposing scale 52 applied to the cover plate 19.

By making the plate-ports 21 substantially 30 square, rather than round, a full opening is always provided in any adjustment of the reed block for the through passage of the air to operate the reeds, resulting in a louder and more uniform quality of tone. Furthermore, the spacing of these ports and their relationship to the 35 rectangularly-shaped, aligned outlets 38 in the top of the reed block assure proper air control in any transposing adjustment desired by the player without leakage from one reed chamber to another, it being noted that in any position of such 40 adjustment that the transverse partitions 34 of the reed block overlie and register with the companion connecting webs 22 between the plate-ports 21 to effectually check any undesirable escape of air between adjoining chambers. Also, 45 the spacing webs 23 between the rows of plate-ports overlie and register with the longitudinally-partitioned spaces provided by the partitions 30 jointly with the reed plates 36 and sealing strips 37. The top side of the reed block 14 is provided 50 with a marginal sealing strip 53 and the side and bottom edges of the slideable reed plates 36 have similar sealing strips 54 thereon to prevent 55 leakage of air about the same.

The reed block is provided with longitudinal 60 guide flanges 55 and is detachably held in sliding relation to the underside of the plate 20 by two sets of pivoted yieldable clamping jaws 56, 57, the jaws 56 being releasably retained in an operative position by companion spring catches 58 and the jaws 57 being similarly retained by latching levers 59.

The reed block valves 27 are hinged along one 65 of their longitudinal edges to the bottom wall 29 of the block 14 so as to swing sidewise or laterally to simultaneously expose all of the ports 28 companion thereto to thereby obtain uniformity of tone of all the reeds associated therewith. Each valve has a hook-like lug 60 applied thereto with which a vertically-swinging actuating arm 61 engages for controlling the opening and closing

movements of the valve, a spring 62 bearing on such arm for normally urging the valve to its closed position. These valves are arranged in two rows and the actuating arms of that row remote from the keyboard have pivoted extensions 63 operatively connected thereto which terminate at their outer ends in upwardly-bent portions 64 disposed in alined relation with like portions 65 formed on the companion actuating arms 61 of that row of valves nearest the keyboard, whereby such portions are disposed side by side in uniformly spaced relation, being guided in a slotted bar 66 applied to the adjoining side of the reed block and terminating at their free ends above such bar in alined, laterally-bent tappet fingers 67. Projecting from the inner ends of the playing keys 16, 17, and extending in longitudinally alined relation through a rubber or like diaphragm 68 in the adjoining top wall of the windchest 13 to prevent escape of air from the latter, are laterally-bent rods 69 which terminate at their free ends in downwardly-bent lugs 70 disposed in parallel longitudinally-spaced relation opposite the valve-actuating arm portions 64, 65 and in correlation with the tappet fingers 67 thereof to open the reed valves 27 when the playing keys are depressed. The spacing of the row of bent portions 64, 65 of the respective valve-actuating arms and the parallel row of opposing lugs 70 of the key-rods 69 is such that these parts are always in their proper operative related positions for any transposing adjustment of the reed blocks.

The switch or control levers 18, which govern the opening and closing of the reed-controlling valves 24 to imitate the tonal effects of different musical instruments are so designed that by a slight touch of any of said levers the companion valve or valves connected thereto are opened, and should any other lever be then in a selected operative position, it would be automatically moved to an inoperative valve-closing position. Disposed over these reed-controlling valves in spaced relation thereto is a plate or platform 11 having a longitudinal row of ears 12 rising therefrom to which the levers 18 are fulcrumed intermediate their ends for vertically-swinging movement. Forwardly of these ears and depending from the underside of this platform are similar ears 13 in which individual horizontal rock shafts 14, one for each control lever, are journalled. Operatively disposed between each control lever and its companion rock shaft and guided on the bottom side of the platform for movement transversely thereof is a slide bar 75 having an opening 76 at one end thereof for receiving a depending lug 77 formed on the control lever 18, and a projection 78 at its other end in abutting relation to one end of a radial pin 79 fixed on the companion rock shaft. A link bar 80 is disposed over and operatively connected by suitable couplings 81 to one or more of the reed-controlling valves 24 associated with a given control lever 18 and abuts adjacent its inner end against the other end of the pin 79, so that when the control lever is pressed to a selective position, its lug 76 shifts the slide bar 75 forwardly to cause its projection 78 to actuate the rock shaft 14 and accordingly shift the valve-governing link bar in a direction to simultaneously open the valves connected therewith and thereby render those reeds of the accordion operative for imitating a violin or other instrument. Operatively associated with each slide bar is a retaining latch 82 which is adapted in the selected position of its control lever, to engage a hook 83 on such bar to positively retain the

parts in an operative selective position. Each latch 82 is pivoted at 84 to the underside of the platform 11 and the several latches are connected forwardly of their pivots to a common longitudinal link 85, a spring 86 connected at one end to one of the latches and its other end to the platform serving to yieldingly resist movement of the link out of a latching position. A spring 87 is connected to each control lever for urging it and the parts connected thereto to a normal inoperative position when its latch is released. By this construction, as a control lever 18 is depressed to a selective position, the link 85 is first bodily shifted longitudinally by a wedging action between the companion slide bar and latch to release any other latch 82 which might have been engaged at the time and cause the companion spring 87 to restore its lever and valves controlled thereby to their inoperative position, and thereafter project the slide bar 75 of the depressed lever into retaining engagement with its latch, at which time the spring 86 urges the link in the opposite direction to its latching position.

The playing keys 16 are preferably individually adjustable to readily correct for any unevenness in the finger-engaging portions thereof over the whole keyboard or to render the key action shallow or deep to suit the player. For this purpose each key is fulcrumed intermediate its ends on a common pivot 88, a spring 89 bearing on the underside of the forward end of the key to bring its downwardly facing shoulder 90 at its rear end against a suitable stop 91. A saw cut or slot 92 extends from the rear end of the key above its pivot to a point around and forwardly of such pivot to permit a relative displacement of the resulting portion of the key. Arranged in this slot is a bow spring 93 and fitted in the upper rear portion of the key and spanning the slot and extending through an opening in the spring is a headed adjusting screw 94. By turning the screw home or tightening it, that portion of the key forwardly of its pivot is accordingly displaced relatively to the fixed rear end and sprung upwardly to raise the level of its finger-engaging surface, the slot 92 being contracted and the bow spring 93 being compressed. Upon loosening the screw, the spring forces the front section of the key to spring downwardly in a reverse direction to lower the level of its finger-engaging surface. During such adjustments of level, the rear portion of the key remains in fixed abutting relation against the stop 91 and the connections from the key to the reed control valves are therefore not disturbed or interfered with.

I claim as my invention:

1. In an accordion, a unitary reed block having a plurality of groups of reed chambers therein, each group including a plurality of parallel rows of reed chambers disposed in alined transverse relation, key-operated valves operatively associated with one end of each set of transversely alined chambers, and manually-controlled valves operatively associated with the opposite ends of each parallel row of reed chambers.
2. In an accordion, a unitary reed block having a plurality of groups of reed chambers therein, each group including a plurality of rows of reed chambers extending lengthwise of the block and disposed in alined relation transversely thereof, a plurality of rows of transversely-disposed valves in controlling relation with one end of each set of transversely-alined chambers, a plurality of rows of longitudinally-disposed valves in controlling relation with the opposite

ends of each parallel row of reed chambers, player keys corresponding in number and operatively connected to said transversely-disposed valves, and selector levers operatively connected in predetermined relation to said longitudinally-disposed valves.

3. In an accordion, a unitary reed block having a plurality of groups of reed chambers therein, each group including a plurality of rows of reed chambers extending lengthwise of the block and disposed in alined relation transversely thereof, a plurality of rows of transversely-disposed valves in controlling relation with each set of transversely-alined chambers, each valve being fulcrumed at a side edge thereof and along the companion set of chambers, individual connections for said valves pivotally mounted on the reed block and terminating at one side of the fulcrum thereof in valve-engaging arms and at the opposite side thereof and at substantially right angles to such arms in a row of actuatable elements disposed in longitudinal parallel relation to said block, and player keys provided at their inner ends with actuator elements disposed in parallel relation lengthwise of the reed block for operative engagement with the companion valve-connecting elements.

4. In an accordion, a windchest, a unitary reed block therein having a plurality of groups of reed chambers, each group including a plurality of rows of reed chambers extending lengthwise of the block and disposed in alined relation transversely thereof, a plurality of rows of transversely-disposed valves in controlling relation with each set of transversely-alined chambers, individual connections for said valves mounted on the reed block and terminating at one side thereof in a row of actuatable elements in longitudinal parallel relation to said block, player keys provided at their inner ends with actuator elements disposed in opposing relation to the reed block and in alined relation lengthwise thereof for operative engagement with the companion valve-connecting elements, and a flexible diaphragm in that wall of the windchest adjoining the player keys and through which the actuator elements thereof extend in air-sealing engagement therewith.

5. In an accordion, a windchest including a plate having a plurality of rows of ports disposed lengthwise thereof, a unitary reed block guided for longitudinal adjustment in said windchest for transposing purposes and having rows of reed chambers extending lengthwise thereof for selective registration at one end with said plate ports, a plurality of rows of valves in controlling relation with said reed chambers, individual connections for said valves pivotally mounted on the reed block at one side thereof and terminating at one side of the fulcrums thereof in valve-actuating arms overlying the valved wall of the block and at the opposite side thereof in a row of equally-spaced actuatable elements disposed along the adjoining side wall of the block and terminating in alined tappet fingers, and player keys provided at their inner ends with like-spaced actuator elements disposed in a row in opposing relation to said row of actuatable elements for engagement with the tappet fingers thereof for controlling the movements of the valves to their open and closed positions in different positions of adjustment of the reed block.

6. In an accordion, a windchest including a top plate having a plurality of rows of ports disposed lengthwise thereof, a keyboard for the player

keys extending from the top side of said windchest, a unitary reed block guided for longitudinal adjustment in said windchest and on the underside of the top plate thereof for transposing purposes and having rows of reed chambers for selective registration at their upper ends with the companion rows of plate-ports, a plurality of rows of valves corresponding in number to the player keys applied to the bottom side of the reed block in controlling relation with the lower ends of the reed chambers, individual connections for said valves mounted on said reed block and terminating at that side thereof adjoining the keyboard in a longitudinal row of equi-spaced actuatable elements, a flexible diaphragm applied to the windchest along the adjoining inner side of the keyboard, and actuating connections extending from the player keys through said diaphragm in air-sealing engagement therewith and terminating at their inner ends in actuator elements disposed in a longitudinal row in opposing operative relation to said valve-connecting elements.

7. In an accordion, a windchest including a top plate having a plurality of rows of ports disposed lengthwise thereof, a keyboard for the player keys extending from the top side of said windchest, a unitary reed block guided for longitudinal adjustment in said windchest and on the underside of the top plate thereof for transposing purposes and having rows of reed chambers for selective registration at their upper ends with the companion rows of plate-ports, a plurality of rows of valves corresponding in number to the player keys applied to the bottom side of the reed block in controlling relation with the lower ends of the reed chambers, individual connections for said valves mounted on said reed block and terminating at that side thereof adjoining the keyboard in a longitudinal row of equi-spaced actuatable elements, a flexible diaphragm applied to the windchest along the adjoining inner side of the keyboard, actuating connections extending from the player keys through said diaphragm in air-sealing engagement therewith and terminating at their inner ends in actuator elements disposed in a longitudinal row in opposing operative relation to said valve-connecting elements, and reed-controlling valves applied to the top side of said ported plate, there being one of such valves for each row of plate-ports, for selectively controlling the companion reed chambers in the reed block.

8. In an accordion, a windchest including a top plate having a plurality of rows of ports disposed lengthwise thereof, a keyboard for the player keys extending from the top side of said windchest, a unitary reed block guided for longitudinal adjustment in said windchest and on the underside of the top plate thereof for transposing purposes and having rows of reed chambers for selective registration at their upper ends with the companion rows of plate-ports, a plurality of rows of valves corresponding in number to the player keys applied to the bottom side of the reed block in controlling relation with the lower ends of the reed chambers, individual connections for said valves mounted on said reed block and terminating at that side thereof adjoining the keyboard in a longitudinal row of equi-spaced actuatable elements, a flexible diaphragm applied to the windchest along the adjoining inner side of the keyboard, actuating connections extending from the player keys through said diaphragm in air-sealing engagement therewith and terminating at their inner ends in actuator elements disposed in a longitudinal row in opposing operative relation to

said valve-connecting elements, a plurality of reed-controlling valves disposed longitudinally in rows over the companion rows of ports in the reed block plate for selectively controlling the companion rows of reed chambers to imitate the tonal effects of different musical instruments, and a plurality of levers each operatively connected collectively to a predetermined number of said reed-controlling valves for governing their simultaneous movement to open and closed positions.

9. In an accordion, a windchest including a top plate having a plurality of rows of ports disposed lengthwise thereof, a keyboard for the player keys extending from the top side of said windchest, a unitary reed block guided for longitudinal adjustment in said windchest and on the underside of the top plate thereof for transposing purposes and having rows of reed chambers for selective registration at their upper ends with the companion rows of plate-ports, a plurality of rows of valves corresponding in number to the player keys applied to the bottom side of the reed block in controlling relation with the lower ends of the reed chambers, individual connections for said valves mounted on said reed block and terminating at that side thereof adjoining the keyboard in a longitudinal row of equi-spaced actuatable elements, a flexible diaphragm applied to the windchest along the adjoining inner side of the keyboard, actuating connections extending from the player keys through said diaphragm in air-sealing engagement therewith and terminating at their inner ends in actuator elements disposed in a longitudinal row in opposing operative relation to said valve-connecting elements, a plurality of reed-controlling valves disposed longitudinally in rows over the companion rows of ports in the reed block plate for selectively controlling the companion rows of reed chambers to imitate the tonal effects of different musical instruments, and a plurality of levers each operatively connected collectively to a predetermined number of said reed-controlling valves for governing their simultaneous movement to open and closed positions, and means operatively connected to said levers for individually latching them in a selective operative position and for automatically causing the release of a previously-selected lever to an inoperative position.

10. In an accordion, a windchest having a top plate containing a plurality of longitudinal rows of equi-spaced ports, said ports being rectangular in shape, valves applied to said plate for controlling the rows of ports therein, and a reed block mounted in said windchest in overlying relation to the underside of its top plate and adjustable lengthwise thereof to predetermined positions for transposing purposes, said block having corresponding rows of key-governed reed chambers therein for registering communicating relation with said plate-ports, each of said reed chambers being also rectangular in shape and having a longitudinal dimension approximately twice that of the plate-ports, whereby in certain adjustments of the reed block certain of its chambers are adapted to register individually with two of the plate-ports.

11. In an accordion, a reed block having longitudinal and transverse partitions therein providing longitudinal rows of transversely aligned chambers, two of the resulting end rows of chambers having reed-bearing plates therein disposed substantially centrally thereof and the middle row of chambers having two parallel rows of

reed-bearing plates therein disposed substantially centrally thereof, and a valve-bearing plate applied to one face of said block and having longitudinal rows of ports therein transversely aligned with said chambers, the end rows of such ports communicating with those portions of the companion end chambers between the longitudinal partitions and the reed-bearing plates therein, and the middle row of such ports communicating with that portion of the middle chamber between the reed-bearing plates therein, the opposite ends of said port-communicating chamber portions being closed and the remaining portions of said respective chambers at such corresponding ends being open.

12. In an accordion, a reed block having a pair of longitudinal partitions therein and transverse partitions spaced to provide transversely aligned chambers, parallel rows of reed-bearing plates arranged in said chambers between and slidably supported on the transverse partitions, there being two rows of such plates in the middle chamber provided by the longitudinal partitions and one row of such plates in the end chambers, said plates being so spaced relatively to the longitudinal partitions as to provide reed chambers of uniform dimensions, longitudinal sealing strips applied to one face of the block between the longitudinal partitions and the adjoining end rows of reed plates and between the middle row of reed plates, and a cover plate applied to the opposite face of said reed block and having longitudinal rows of ports therein transversely aligned with the companion reed chambers, one row of said ports communicating with that portion of the middle chamber between the rows of reed-plates therein and the other rows of such ports communicating, respectively, with those portions of the end chambers between the longitudinal partitions and the adjoining rows of reed plates.

13. In an accordion, a plurality of rows of reed-controlling valves, control levers each operatively connected collectively to certain of said valves for simultaneously moving them to an open and closed position, and means for connecting each of said levers to predetermined groups of said valves, comprising a slide bar operatively connected to its companion lever, a pivoted latch engageable with said slide bar for releasably latching it in its valve-opening position, a shiftable link operatively connected to the valves of the companion group, and an operative connection between said slide bar and said link for shifting the latter to a valve-opening position when the former is projected by the companion lever to a selective operative position.

14. In an accordion, a plurality of rows of reed-controlling valves, control levers each operatively connected collectively to certain of said valves for simultaneously moving them to an open and closed position, and means for connecting each of said levers to predetermined groups of said valves, comprising a slide bar operatively connected to its companion lever, a pivoted latch engageable with said slide bar for releasably latching it in its valve-opening position, a shiftable link operatively connected to the valves of the companion group, an operative connection between said slide bar and said link for shifting the latter to a valve-opening position when the former is projected by the companion lever to a selective operative position, a spring connected to each control lever for normally urging it to a released position, and a spring-urged link constituting a common support for each latch adapted to shift any engaged latch

to a released position when any other control lever is projected to a selective position.

15. In an accordion, a reed block having rows of transversely-aligned reed chambers therein, valves for controlling each group of transversely-aligned chambers, each valve being fulcrumed at a longitudinal side edge thereof to the block and along the companion group of chambers, player keys operatively connected to said valves for opening them, and means for adjusting said keys to render action shallow or deep to accordingly open said valves in less or greater degree.

16. In an accordion, a reed block having two groups of reed chambers therein, each group consisting of a plurality of longitudinal rows of chambers transversely aligned, two rows of valves in operative relation with the transversely-aligned chambers of the two groups, companion rows of actuating levers pivotally connected to the opposite sides of the reed block at their free ends in opposing relation and operatively connected to the valves for individually controlling them, one row of levers including pivoted extensions operatively connected thereto at one end and extending

between the valves and levers of the other row whereby such extensions and said other row of levers are equally spaced, this last-named row of levers and the free ends of the extensions of the companion row of levers terminating in longitudinal aligned tappet fingers disposed parallel to the adjoining wall of the reed block.

17. In an accordion, a windchest having a plurality of longitudinal rows of equi-spaced, square-shaped ports in a wall thereof, a reed block mounted in said windchest for adjustment lengthwise thereof to predetermined positions and having companion rows of reed chambers therein for registering communication with the windchest-ports, said reed chambers being rectangular in shape and substantially twice as long as the square-shaped ports, player key-operated valves associated with said reed chambers, means connected to said reed block for adjusting it to different positions proportionate to the dimensions of the square-shaped ports, and means for visibly indicating to the player the different adjustment of the reed block for transposing purpose.

FRANK KOSTKA.
